UNITED STATES PATENT OFFICE.

THEODORE M. SMITH, OF NEW YORK, N. Y., ASSIGNOR OF ONE-HALF TO LAURA C. PHELAN, OF NEW YORK, N. Y.

DESIGN FOR AN ORNAMENT.

54,338.

Specification for Design.

Patented Dec. 23, 1919.

Application filed March 15, 1918. Serial No. 222,744. Term of patent 3½ years.

To all whom it may concern:

Be it known that I, THEODORE M. SMITH, a citizen of the United States, residing at 657 Caldwell Ave., in the county of Bronx and State of New York, have invented a new, original, and ornamental Design for an Ornament, of which the following is a specification, reference being had to the accompanying drawing, forming part thereof.

In the drawing, the figure is a perspective view of the patriotic ornament.

I claim:—

The ornamental design for an ornament, as shown.

THEODORE M. SMITH.
